UNITED STATES PATENT OFFICE.

CHARLES WICKSTEED, OF KETTERING, ENGLAND.

SAWING-MACHINE.

1,067,955.

Specification of Letters Patent. Patented July 22, 1913.

Application filed June 2, 1911. Serial No. 630,829.

To all whom it may concern:

Be it known that I, CHARLES WICKSTEED, a subject of the King of England, residing at Kettering, in the county of Northampton, England, have invented certain new and useful Improvements in Sawing-Machines, of which the following is a specification.

This invention relates to sawing machines. 10 The use of mechanically-guided hack-saws for cutting metal is well known. Such saws have been applied to the cutting of metal articles held on a stationary fixed table, and this application has been found 15 to be of considerable practical value. Moreover, combination machine tools have hitherto been proposed in which a circular neck work holder was adapted to turn in sockets so as to secure a larger range of angular adjustment for the work. The present inventor having found that existing hack-sawing machines with fixed work-tables possess limitations due to the fact that the table is fixed has invented the combination with 20 a saw or a plurality or gang of saws and guiding-devices therefor of a work-supporting table which as the characteristic feature of this invention is such that it can adjust the work in relation to the saw to any position desired, for instance angularly in different planes or to different levels as well as to different angles, and in addition, or instead if desired, to different positions horizontally by means of a slide or crossed slides. 25 In the said combination any convenient construction of table can be used provided it is capable of adjusting the work as aforesaid. For instance the well-known type of adjustable table commonly used on the upright 30 standard of a reciprocating shaping-machine can be employed.

In the accompanying drawings—Figure 1 illustrates in side elevation a construction of improved hack-sawing machine according to this invention, comprising an adjustable table of the shaping-machine type; Fig. 2 illustrates in side elevation and Fig. 3 in end elevation a detail, hereinafter described, of the machine illustrated in Fig. 1, the 45 scale of Figs. 2 and 3 being larger than that of Fig. 1.

With reference first to Fig. 1 the base B has vertical guides G upon its front face. On these guides travels the table, which is in three parts T¹, T², T³ and can be moved up and down along the guides G by the adjusting-screw S¹ engaged with the part T¹. The companion part T³ of the table can have upon it clamping-jaws or devices of any usual or convenient type capable of holding the work firmly. It is pivotally mounted on the part T² and is adjustable in relation thereto by a screw S³ which gears into a toothed quadrant Q on the said part. The screw S³ is used to adjust the part T³ in relation to the part T² about a horizontal axis which is perpendicular to the front face of the machine.

The cross-slide or part T² of the table slides transversely across the front face of the machine on a guide on the part T¹, being movable along this guide by means of the horizontal cross-screw S².

A hack saw H is mechanically reciprocated more or less horizontally above the compound table T¹ T² T³ in a plane perpendicular to the front face of the machine. The saw is supported in the following way. A gauntlet formed of two rods L, a bar L² and a third rod L³ is pivotally supported at B¹ upon the standard B. The rods L, seen most clearly in Fig. 3, carry a cross-head H² slidably mounted on the rods L so as to be free to reciprocate back and forth thereupon. The cross-head H² has a drooping tail-like portion H⁵ to which a connecting rod R is attached, the other end of the connecting rod being in engagement with a crank pin C¹ on a crank disk C. The crank disk is carried by a shaft A mounted in the support which carries the pivot B¹ of the gauntlet L L².

The shaft A, by means of an eccentric A¹ and eccentric rod A², operates hydraulic means (which form no part of the present invention) by which, through the rod A³, the gauntlet is tilted slightly in a clockwise direction on each return stroke of the saw H so as to raise the teeth of the latter from the work on the return stroke but so as to allow the saw to fall on its work again during the forward stroke.

Convenient means are provided whereby the saw frame H^1 which is reciprocated in company with the cross-head H^2 can be adjusted relatively to that cross-head and held firmly upon it nearer to one or the other end of it.

The means of adjustment in the illustrated example shown in Figs. 2 and 3 in greater detail than in Fig. 1 consist of a slider H^3 adjustable endwise in guides which it fits in the cross-head H^2 . Bolts H^4 project from the slider H^3 through longitudinal slots H^6 in the cross-head and serve to clamp the saw frame H^1 borne by the slider H^3 in any position to which it may be moved endwise. This adjustment affords a convenient means of locating the limits of travel of the saw relatively to work clamped upon any part of the table T^3 .

20 The saws H can be adjusted laterally (as viewed in Fig. 3) with relation to one another so that cuts can be taken simultaneously side by side in a piece of work, the saw holders H^1 being slidably mounted on transverse rods G^2 and provided with clamping screws G^1 to enable this to be done.

The cross-head H^2 slides upon rods L forming one end of a lever L , L^2 pivoted to the frame of the machine at B' . Upon the portion L^2 of the lever L , L^2 is fixed a rod L^3 parallel with it and on the rod is a weight W which can slide along it and be fixed upon it in any chosen position by means of the set screw W' . This weight can be shifted to one side or the other of the fulcrum B' so as to vary the pressure with which the saw bears upon the work.

It will be seen that the sawing machine herein described is capable of executing a great variety of work with accuracy and despatch. It is capable, for example, when the two saws shown in Fig. 3 are separated from one another, of performing work, which ordinarily would have to be carried out in a milling machine with straddle mills, with greater rapidity than that which would be attained in a milling machine. This is owing to the fact that portions of material which would have to be entirely removed in the form of cuttings by the milling machine, can be removed as a block by making cuts with the saw which meet one another. Owing to the way in which the saw or saws are arranged to sink steadily in their kerfs, together with the means whereby the work can be accurately presented to the saw or saws, work such as that which has just been referred to can be carried out in a manner which heretofore has been quite impossible.

Work firmly clamped on the part T^3 of the table can be presented to the saw at various levels and various angles and can

be shifted across the face of the machine by the cross slide T^2 . Work can be easily and rapidly carried out in a machine thus fitted that could not be carried out except with difficulty and delay on a machine having a table not thus adjustable.

What I claim as my invention and desire to secure by Letters Patent is:—

1. In a reciprocating sawing machine, the combination of a support, a saw mounted thereon, means for confining the movements of the saw within a vertical plane, means for reciprocating the saw in that plane, means for applying yielding pressure to the saw during the cutting stroke, a work-table on the support, means for giving to the work-table sliding adjustment in two directions, and means for giving to the work-table rotational adjustment, substantially as set forth.

2. In a reciprocating sawing machine, the combination of a support, a saw mounted thereon, means for confining the movements of the saw within a vertical plane, means for reciprocating the saw in that plane, means for applying yielding pressure to the saw during the cutting stroke, a work-table on the support, means for giving to the work-table sliding adjustment in two directions at right-angles to one another, and means for giving to the work-table rotational adjustment about an axis which is at right-angles to both directions of sliding adjustment and is parallel to the plane containing the path of the saw, substantially as set forth.

3. In a reciprocating sawing machine, the combination of a support, a saw mounted thereon, means for confining the movements of the saw within a vertical plane, means for reciprocating the saw in that plane, means for applying yielding pressure to the saw during the cutting stroke, a member arranged to slide upon the support, means whereby its position in its sliding path upon the support may be adjusted, a second member carried by and arranged to slide upon the first, means whereby its position in its sliding path upon the first-mentioned sliding member may be adjusted in a direction at right-angles to the direction of adjustment of the first, and a work-table pivotally supported by the second sliding member about an axis which is at right-angles to the directions of adjustment of both sliding members and is parallel to the plane containing the path of the saw, substantially as set forth.

4. In a reciprocating sawing machine, the combination of a support, a straight-line-motion guide for the saw pivotally mounted upon the support, a load for the guide whereby yielding pressure is applied to the

saw during the cutting stroke, means for reciprocating the saw, a work-table on the support, means for giving to the work-table sliding adjustment in two directions and 5 means for giving to the work-table rotational adjustment substantially as set forth.

In testimony whereof I have signed my

name to this specification in the presence of two subscribing witnesses.

CHARLES WICKSTEED.
